UNITED STATES PATENT OFFICE

JOHN H. FRIEDMAN, OF TIFFIN, OHIO, ASSIGNOR TO THE NATIONAL MACHINERY CO.,
OF TIFFIN, OHIO

METHOD OF AND MECHANISM FOR TRIMMING FORGINGS

Application filed July 21, 1927. Serial No. 207,483.

This invention relates to a method of trimming forgings produced in heading or forging machines, one of the objects being to provide a means whereby, during one cycle of operation of the machine the forging will be severed from the stock and the flashing trimmed therefrom.

With the foregoing and other objects in view the invention resides in certain novel details of construction and in the steps of the method hereinafter more fully described and pointed out in the claims, it being understood that various changes may be made within the scope of the claims without departing from the spirit of the invention.

In the accompanying drawings there has been illustrated the several methods involved in the formation of a forging and the trimming of the flashing therefrom.

20 In said drawings:

Figure 1 is a transverse section through gripping dies showing the stock in position therein subsequent to the forging operation and showing the flashing between the gripping dies and the forging die.

Figure 2 illustrates the feeding operation wherein the forging is partially severed from the stock.

Figure 3 is a section through the gripping dies showing the forging completely severed and positioned preparatory to the severance of the flashing.

Figure 4 is a view similar to Figure 3 showing the relative positions of the parts 25 after the forging has been punched out of its flashing.

Referring to the figures by character of reference 1 designates the stationary gripping die of a forging machine and 2 designates the movable gripping die. The forging or heading die has been shown at 3. These dies are used during the first steps of the method wherein the stock, indicated at S, is fed between the gripping dies and, 40 while firmly held is subjected to the action of the forging die 3 which shapes the projecting portion of the stock and at the same time necessarily produces a flashing such as indicated at F. It is designed to partially 45 sever the forging from the stock by means

of a shear 4 and thereafter the forging is conveyed to a pair of dies indicated at 5 and 6 which act to support the forging with the flashing F extended into grooves 7 formed in trimming dies 8 and which trimming dies 55 fit snugly about that portion of the forging from which the flashing is to be removed. During the positioning of the forging between the dies 5 and 6 and the dies 8, a shear 9 is utilized for completely severing the 60 forging from the stock, the die 6 being utilized to press the stock toward the die 5 and against the shear to complete the shearing operation, as disclosed, for example, in my copending application number 207,482, 65 filed July 21, 1927. While the forging is being directed against the shear 9 and toward the die 5, the die 6 will of course move to position between and close to the trimming dies 8 and the shear 9. If preferred, 70 this severing operation can take place immediately following the positioning of the forging between the dies. In the structure illustrated the shear 9 has a recess 10 adapted to be brought to position in line with the 75 forging after said forging has been severed from the stock. Following this final severance, a punching die 11 is brought against one end of the forging and will force it downwardly relative to the trimming dies 8 so that said forging will be punched out of the 80 flashing F which will be left within the grooves 7. During this punching operation the forging is received by the recess 10 as shown in Figure 4. Thereafter the dies are 85 opened so as to release the forging and the severed flashing.

It is to be understood of course that the step of partially severing the forging from the stock, as illustrated in Figure 2, is not 90 essential in carrying out this invention.

What is claimed is:

1. The combination with dies for receiving a forging, and trimming dies adjacent thereto for receiving a portion of the forging, said trimming dies having grooves for the reception of a flashing on the forging, of a shear for severing the engaged forging from stock extending beyond the first named dies, there being a recess in the shear adapted 95 to 100

to register with one end of the severed forging, and means for punching the forging out of its flashing in the trimming dies and into the recess in the shear.

- 5 2. A combination with a stationary and a movable die for receiving therebetween a forging at one end of a length of stock, and trimming dies movable toward each other adjacent the first named dies for receiving 10 a portion of the forging therebetween, said trimming dies having grooves for the reception of the flashing of the forging, of a shear for severing the forging from the stock, said shear having a recess for receiving 15 one end of the forging, said first named movable die being shiftable against the stationary die to force a portion of the forging against the shear thereby to sever the forging from the stock of which it is a part and 20 bring one end of the forging opposite the recess in the shear, and means for punching the forging into the recess in the shear, thereby to strip the forging from the flashing in the trimming dies.

- 25 3. The combination with dies for engaging a forging formed of a portion of a length of stock, of trimming dies having grooves for receiving flashings on the forging, a shear for severing the forging from the stock, said shear having a recess adapted to align with one end of the severed forging, a die working between and close to the trimming dies and the shear, and means for 30 punching the forging to strip it from the flashing engaged by the trimming dies and direct one end of the forging into the recess in the shear.

- 40 4. The method of trimming solid blanks which includes the steps of offsetting one end portion of a length of solid stock to form a partly severed blank, shaping the partly severed blank to form a flash, transferring the blank by means of the adhering length of stock to a position where it will be supported by its flashing, completing the severance of the solid blank at the point of offset, and finally punching the blank out of its supported flashing and into the severing means.

- 50 5. The combination with dies for guiding a blank and for receiving the flashing on the blank, of means for severing the blank from stock extending beyond the dies, and means for punching the blank out of its flashing 55 there being a clearance in the severing means for receiving one end of the blank following said punching operation, and prior to the return of the severing means to its initial position.

- 60 6. In testimony that I claim the foregoing as my own, I have hereto affixed my signature.

JOHN H. FRIEDMAN.
